Term of patent 14 years

Int. Cl. D23—02

U.S. Cl. D23—58

FIGURE 1 is a perspective view of a portable lavatory unit showing my new design;

FIGURE 2 is a rear elevational view thereof;

FIGURE 3 is a front elevational view thereof;

FIGURE 4 is an elevational view taken from the right side thereof, the left side being a mirror image of the side shown;

FIGURE 5 is a top plan view thereof;

FIGURE 6 is a cross sectional view taken on the line VI—VI of FIGURE 5; and

FIGURE 7 is a bottom plan view thereof.

The dominant features of my design reside in the portions shown in full lines.

I claim:

The ornamental design for a portable lavatory unit, as shown and described.
